UNITED STATES PATENT OFFICE.

ROBERT E. EINSTEIN, OF ST. LOUIS, MISSOURI, ASSIGNOR TO ST. LOUIS FROG & SWITCH COMPANY, OF ST. LOUIS, MISSOURI, A CORPORATION OF MISSOURI.

TONGUE-SWITCH.

1,112,058.

Specification of Letters Patent. Patented Sept. 29, 1914.

Application filed May 12, 1914. Serial No. 837,993.

To all whom it may concern:

- Be it known that I, ROBERT E. EINSTEIN, a citizen of the United States, residing at St. Louis, Missouri, have invented a certain new and useful Improvement in Tongue-Switches, of which the following is a full, clear, and exact description, such as will enable others skilled in the art to which it appertains to make and use the same.
- This invention relates to tongue switches and has for its main object to provide a switch in which the tongue is provided at its heel end with an integral pivot pin of relatively great length and area, whose lower end rests on a horizontally disposed bearing surface on the body part of the switch, and whose front side is engaged by a device that locks the tongue in operative position in the body part, the rear half of the tongue having a vertically disposed convex bearing surface that is embraced by a vertically disposed concave bearing surface on the body part of the switch.
- Another object is to provide a tongue switch that comprises means of novel construction for locking the tongue in operative position, and for adjusting the tongue longitudinally of the body part of the switch to compensate for wear on the coöperating pivotal bearing surfaces on the body part and on the pivot pin of the tongue, said means being so designed that it can be applied and removed easily. And still another object is to provide a tongue switch in which the parts are so designed that very little finishing of the castings is required, thereby producing a device that is well adapted for manganese steel.
- Figure 1 of the drawings is a top plan view of a switch constructed in accordance with my invention. Fig. 2 is a vertical transverse sectional view taken on the line 2—2 of Fig. 1. Fig. 3 is a vertical longitudinal sectional view taken on the line 3—3 of Fig. 1. Fig. 4 is a vertical transverse sectional view taken on the line 4—4 of Fig. 1. Fig. 5 is a side elevational view of the tongue. Fig. 6 is a vertical longitudinal view of the body part. Fig. 7 is a perspective view of the wedge; and Fig. 8 is a perspective view of the bearing mem-

ber that is interposed between the wedge and the pivot pin on the tongue.

Referring to the drawings which illustrate the preferred form of my invention, A designates the body part of the switch, which is provided with a horizontally disposed bearing surface 1, on which the tongue B slides laterally. At the heel end of the tongue is an integral pivot pin B', which is comparatively long and of relatively great area, said pivot pin projecting downwardly into a chamber A' in the body part A that is provided with a horizontally disposed bearing surface 2, on which the flat bottom face of the pivot pin B' rests, as shown in Fig. 3. The rear half of said pivot pin is straight or provided with a vertically disposed convex bearing surface 3, and the body part of the switch is provided with a vertically disposed concave bearing surface 3* that surrounds the convex bearing surface on said pivot pin, thus producing a switch in which the body part and the tongue are provided with coöperating vertically disposed bearing surfaces of approximately twice the depth of the thickness of the tongue proper for resisting the lateral forces at the heel end of the tongue. The pivot pin B' can either be formed solid or hollow, the pivot pin of the tongue herein shown being hollow.

The tongue B is locked in the body part of the switch in such a way that the heel end portion of the tongue cannot rise vertically accidentally, and in the embodiment of my invention herein shown the means employed for this purpose consists of a lip 4 on the rear side of the pivot pin B' at the lower end of same, which projects into a notch 4* formed in the rear wall of the chamber A' and a member 5 that laps over or embraces a tapered part on the front side of the pivot pin B'. The retaining member 5 extends transversely of the chamber A' in front of the pivot pin of the tongue and is provided with an under-cut concave bearing surface that laps over a bearing surface 5* on the pivot pin that tapers upwardly. The end portions of the bearing member 5 extend under the top wall of the chamber A', as shown in Fig. 2, and said member is held pressed tightly

against the pivot pin on the tongue by means of a wedge 6 that is interposed between the member 5 and the front wall 7 of the chamber A', which is inclined as shown in dotted lines in Fig. 1, said wedge being long enough so that the end portions of same will be engaged by the end walls of said chamber.

An adjustable actuating device, which is connected to the wedge 6, is arranged in a housing C that projects laterally from the body part of the switch, as shown in Fig. 1, and in the form of my invention herein shown, said actuating device consists of a rod 8 pivotally connected at 8* to the wedge 6 and provided at its outer end with a cap nut 9, having a rounded end 9* that bears against the end wall 10 of the housing C. By rotating the nut 9 in one direction, the wedge 6 will be forced inwardly, thus moving the tongue B longitudinally of the body part of the switch, so as to compensate for wear on the coöperating bearing surfaces 3 and 3* on the pivot pin of the tongue and on the body part of the switch, respectively. After the nut 9 has been adjusted it is held securely locked in its adjusted position by means of a removable cover 11 on the housing C that is provided with one or more depending wings 12 which engage or embrace the nut 9, so as to prevent it from turning.

A tongue-locking mechanism of the construction above described can be adjusted quickly; the cover or closure for the housing in which said mechanism is arranged serves to secure the locking mechanism in adjusted position and as the rod 8 is combined with the wedge 6 and pivotally connected to same, it can be used as a handle for the wedge during the operation of inserting or removing the wedge. When it is desired to withdraw the wedge, the rod 8 is swung upwardly into such a position that the workman can grasp it easily to withdraw the wedge, and when the wedge is being inserted, the cap nut 9 on the end of the rod 8 is placed in engagement with the end wall of the housing C and downward pressure is applied on the free end of the rod, so as to force the wedge 6 snugly into position between the bearing member 5 and the inclined front wall of the chamber A'.

A tongue switch of the construction above described can be cast easily from manganese steel, owing to the fact that the parts of same are so designed that very little finishing is required, and all of the coöperating surfaces on the tongue and on the body part which require finishing are of such shape that they can be ground easily. The relatively great area of the coöperating vertically disposed bearing surfaces at the heel end of the tongue are ample to restrain the lateral forces at the heel end of the tongue,

and the broad flat bearing surface at the lower end of the pivot pin of the tongue, resting on a horizontally disposed bearing surface on the body part of the switch, eliminates any tendency of the tongue to 70 cock up and reduces wear on the pivot pin to a minimum.

Having thus described my invention, what I claim is:

1. A tongue switch, comprising a body 75 part, a tongue provided at its heel end with an integral pivot pin projecting downwardly into a chamber in said body part and provided with a flat bottom face that rests upon a horizontally disposed bearing 80 surface on the bottom of said chamber, the diameter of said pin being approximately equal to the widest part of the tongue and the rear side of said pin extending flush with the rear end of the heel portion of the tongue, a retaining member in said chamber that bears upon the front face of said pivot pin and locks the tongue in operative position in the body part of the switch, and means on the rear side of said pivot pin that 90 coöperates with the body part of the switch to prevent the heel end portion of the tongue from moving vertically.

2. A tongue switch, comprising a body part, a tongue provided at its heel end with 95 an integral pivot pin projecting downwardly into a chamber in said body part and provided with a flat bottom face that rests upon a horizontally disposed bearing surface on the bottom of said chamber, the 10 transverse diameter of said pivot pin being approximately equal to the diameter of the heel portion of the tongue, a retaining member in said chamber that bears upon the front face of said pivot pin and locks 1 the tongue in operative position in the body part of the switch, and a lip at the lower end of said pivot pin that projects rearwardly from same and enters a notch in the rear wall of said chamber.

3. A tongue switch provided at its heel end with an integral pivot pin whose rear half is convexed and substantially the same cross-sectional area throughout its entire height, the lower end of said pivot pin being flat and resting upon the bottom of a chamber, a lip on said pivot pin that projects from the rear side of same and enters a notch in the rear wall of said chamber, a bearing member extending transversely of said chamber and provided with an undercut concaved surface that embraces a tapered surface on the front half of said pivot pin, and an adjustable device pivotally connected to said member in such a manner that it can be swung upwardly for locking the tongue in operative position in the body part of the switch.

4. A tongue switch, comprising a body part, a tongue, and a locking mechanism for

- 5 said tongue comprising a wedge and an adjusting device for same pivotally connected together in such a manner that said adjusting device can be swung upwardly relatively to the wedge.
5. A tongue switch, comprising a body part, a tongue, and a locking mechanism for said tongue comprising a wedge, an adjustable device pivotally connected at one end 10 to said wedge in such a manner that said adjusting device can be swung upwardly relatively to the wedge, and a stationary wall that acts as an abutment for the opposite end of said device.
- 15 6. A tongue switch, comprising a body part, a tongue, and a locking mechanism for said tongue comprising a wedge, a rod pivotally connected at one end to said wedge in such a manner that it can be moved upwardly into a substantially upright position, and an adjustable cap nut on the opposite end of said rod that is adapted to bear against one wall of the housing in which said rod is arranged.
- 25 7. A tongue switch, comprising a body part, a tongue provided at its heel end with an integral pivot pin, and a locking mechanism for said tongue comprising a wedge and an adjustable device pivotally connected 30 together, a housing in which said adjusting device is arranged, and a removable cover for said housing provided with means for locking said adjusting device.
8. A tongue switch, comprising a body 35 part, a tongue provided at its heel end with an integral pivot pin, and a locking mechanism for said tongue comprising a wedge, a rod pivotally connected to said wedge and provided with an adjusting nut, a housing
- in which said rod is arranged, and a removable cover for said housing provided with a device that engages said nut and prevents it from turning.
9. A tongue switch, comprising a body part provided with a horizontally disposed bearing surface on which the tongue slides and having a chamber at the rear of said bearing surface, a tongue provided at its heel end with an integral pivot pin whose lower end is flat and rests upon the bottom 50 of said chamber, a vertically disposed convexed surface on the rear half of said pivot pin that is embraced by a vertically disposed concave surface on the body part of the switch, a lip that projects rearwardly from 55 said pivot pin and enters a notch in the rear wall of said chamber located adjacent the bottom of same, a bearing member extending transversely of said chamber and embracing a tapered surface on the front side 60 of said pivot pin, a wedge interposed between said bearing member and the front wall of said chamber which is inclined, a rod pivotally connected to said wedge and provided with an adjustable cap nut that 65 has a rounded end, a housing on the body part of the switch for receiving said rod, and a removable cover for said housing provided with a device that engages said cap nut and prevents it from rotating.
- 70 In testimony whereof I hereunto affix my signature in the presence of two witnesses, this sixth day of May 1914.

ROBERT E. EINSTEIN.
